PAUL BAILEY, OF SACRAMENTO, CALIFORNIA.

HYDRAULIC APPARATUS.

1,181,721.

Specification of Letters Patent.

Patented May 2, 1916.

Application filed March 3, 1913. Serial No. 751,758.

To all whom it may concern:

Be it known that I, PAUL BAILEY, citizen of the United States, residing at Sacramento, in the county of Sacramento and 5 State of California, have invented new and useful Improvements in Hydraulic Apparatus, of which the following is a specification.

The present invention relates to hydraulic apparatus, and particularly to an improved 10 means for obtaining a constant discharge of fluid from a source under a variable head or pressure, or for obtaining a discharge increasing or decreasing in any desired relation with a respective increasing or decreasing 15 head or pressure at the source, or for measuring the volume of flow of a liquid from a source.

The object of the present invention is to provide an accurate, automatic, reliable and 20 practical apparatus, operating hydraulically, whereby either a constant volume of flowing water or other liquid can be obtained from the source irrespective of variations of the head or pressure at said source, or whereby 25 a volume of flow can be obtained from the source which volume increases or decreases in any desired relation with a respective increase or decrease of the head or pressure at the source.

30 It is a further object of the invention to provide an accurate, automatic, reliable and practical apparatus, operating hydraulically, whereby the volume of water or other liquid flowing from a source can be measured.

The invention consists of the parts and the construction, and the combination of parts as hereinafter more fully described and claimed, having reference to the accompanying drawings in which—

Figure 1 is a perspective view of one form of the improved hydraulic apparatus arranged to control the flow of liquid. Fig. 2 is a longitudinal section of same through 45 the shutter. Fig. 3 is a detail sectional view of a simple form of accumulative variable weight. Fig. 4 is a view of another form of the improved hydraulic apparatus arranged to measure the volume of fluid issuing from 50 the source.

The present invention involves a means for automatically positively controlling the volume of discharge of a liquid from a conductor, canal, ditch, flume, pipe or other 55 source of supply (2), in which the head or pressure of liquid may vary from time to

time. In many industrial and manufacturing processes, in the filtration of large water supplies, but particularly in irrigation work, it is desirable to have an accurate, simple, 60 practical, automatically operable controlling gate or device for delivering a given quantity of water or other liquid constantly and without variation. It is also sometimes desirable for the controlling gate or device to 65 deliver a volume of flow which increases or decreases in some desired relation with a respective increase or decrease of the head or pressure at the source. It is essential that the device operates reliably without the attention of an operator or attendant. 70

The present invention also involves a means for accurately, automatically and positively measuring the volume of flow of a liquid from a conductor, canal, ditch, 75 flume, pipe or other source of supply (2). In many industrial and manufacturing processes but especially in irrigation work and community water supplies, it is desirable to have an accurate, simple, practical, 80 automatically operable measuring gate or device to measure the volume of flow of water or other liquid from the source of supply (2).

To these ends, I have provided a device 85 including a transverse wall, dam or partition (3), extending across the supply conductor (2) and having a discharge aperture (4) through which water or other liquid escapes from the supply side to the opposite 90 side of the wall, dam or partition (3).

The means for controlling the volume of water or other liquid passing through the transverse wall (3) consists of an appropriately shaped, proportioned and designed 95 shutter (5), operating in an upstream projecting tube (A), which may or may not form the walls of the supply conductor. The shutter is here illustrated as forming the top of this tube (A) which consists of 100 side walls (6) and a bottom (7). The shutter may form either side or the bottom of the tube which must have two sides, a top and a bottom. The shutter is hinged at one end, as at (8), adjacent to or upon the surface of the transverse wall (3), and operates with a snug working fit at its edges between the contiguous walls (6)—(6) of the tube (A). 105

Preferably the shutter (5) approximates 110 the length of the tube (A) in which it operates, and has its swinging upstream edge

bent outwardly as at (9). The function of this outward-turned or outward-bent angular edge (9) of the shutter is to approximately neutralize the tendency of the impacting current to close the shutter toward the opposite face of the tube. While water or other liquid flows through the tube (A) there is an unbalanced hydraulic pressure acting on the shutter tending to push or 10 shove the shutter toward the opposite face of the tube. This unbalanced pressure is the resultant of the static pressures acting on the inside and outside of the tube (A). When the water or other liquid flows 15 through the tube, a portion of the static head or potential energy of the liquid outside the tube (A) must change to velocity head or kinetic energy as it enters and passes through the tube (A). The hydraulic 20 pressure acting to push the shutter (5) away from the opposite face of the tube will therefore be less than the hydraulic pressure acting to push the shutter toward the opposite face of the tube. The turning moment thus 25 produced bears a definite relation to the velocity of the liquid flowing through the tube (A).

In operation, as the shutter (5) is moved toward the opposite face of the tube (A) 30 the volume of water or other liquid flowing through the aperture in the transverse wall (3) will be reduced if the pressure on the supply side remains the same for the cross sectional area of the entrance to the tube 35 (A) is thereby lessened. The free rotary movement of the shutter (5) thus affords an easy means of controlling the discharge volume of the aperture (4) in the transverse wall (3). Then for the purpose of maintaining a constant discharge from the supply (2) when the head or pressure is variable the position of the shutter (5) is regulated by a suitable counterbalancing device 40 which will exert a force on the shutter (5) just sufficient to balance the turning moment produced by the unbalanced hydraulic pressures previously mentioned as acting on the shutter (5). Then for an increase or decrease in the head or pressure at the supply 45 (2) the respectively increased or decreased hydraulic forces acting on the shutter (5) move it to a position in the tube (A), where the cross-sectional area between the shutter (5) and the opposite face of the tube (A) 50 is just sufficient to pass the desired flow of liquid through the apparatus under the respectively increased or decreased head or pressure at the supply (2). The shutter (5) is then counter-balanced in its new position 55 by the respectively increased or decreased force exerted on it by the counter-balancing device which has been designed, proportioned, constructed and adjusted to so act. This counter-balancing device consists of an 60 arrangement of suitable pulleys, wheels,

arcs, or levers as (11) rocking or turning on their shafts or journals as (12), joined on one side of their fulcrum to the shutter (5) by a suitable strap, cable, or other device as (10), and joined on the opposite side of the 70 fulcrum by a suitable connection (13) to a resistant device here shown as an arrangement of weights (14). These weights are constructed in a series of sections (15) which act cumulatively to increase their 75 load as the shutter (5) is moved or pushed toward the opposite face of the tube (A) by the greater hydraulic force acting on the shutter (5) due to an increase of head or pressure at the supply. Likewise the load 80 of the weights (14) will decrease as the shutter moves away from the opposite face of the tube (A) due to the hydraulic force acting on the shutter (5) becoming less when the head or pressure in the supply decreases. Therefore by properly proportioning and spacing these sectional weights and adjusting their connection to the counter-balancing device and shutter (5) they form 85 a simple, reliable, accurate, automatic, resistance to counter-balance the automatically active hydraulic forces producing a 90 turning moment on the shutter (5).

To arrange the apparatus for operation to control the flow so that a volume can be 95 obtained from the source, which volume increases or decreases in any desired relation, with a respective increase or decrease of the head or pressure at the source, it is simply necessary to change the weight or spacing 100 of each of the successive sections (15) of the weight device (14) so that instead of counter-balancing the shutter in a position for each change of head or pressure at the supply (2), that a constant volume of discharge 105 will be maintained, the shutter is counter-balanced by the weight device in a position which will give the desired volume of flow through the gate or apparatus for the head or pressure then acting at the supply (2). 110

To arrange this apparatus for measuring the volume of liquid flowing from a source, it is simply necessary to reconstruct the weight sections (15) and provide the proper indicators and registers for indicating and 115 recording the flow. The weight sections (15) of the weight device (14) will then be so proportioned and assembled that, for the minimum flow through the apparatus, the hydraulic forces, acting on the shutter (5), 120 will be counter-balanced by the load of the cumulative weight device (14) when the shutter is in an approximately horizontal position, and for the maximum flow through the apparatus when the shutter (5) has 125 taken some desired position with its free end nearer the opposite face of the tube (A). For each intermediate volume of flow the shutter (5) will then take a position of equilibrium intermediate between its two 130

extreme positions. It will then be understood that by attaching an indicator (16) to which the motion of the shutter (5) is communicated, the pointer can be made to move over a graduated scale (17) and accurately and automatically indicate the volume of flow of liquid passing through the apparatus at that time. Likewise, the movement of the shutter (5) can be transmitted to some standard or specially devised mechanism (18) which will indicate and record the volume of flow passing through the apparatus at each instant through the day or the total volume of liquid which has passed through the apparatus to any instant during the day.

This apparatus is thus intended to be used under many conditions. The relative proportion, shape, arrangement, and construction of the component parts will therefore change to suit each condition. For the purpose of illustration one particular arrangement and form of the parts has here been shown and described which will best convey an idea of the principle and purpose of this invention. Particularly this applies to the shutter (5), the levers and rocker (11 and 12), the tube (A), and counter-balancing device (14). For instance, the shutter (5) may vary in length with respect to the tube (A), the form of angular turnout (9) may be very different from that shown in the sketch, or the tube (A) may have special features to form easy entrance or exit conditions for the liquid passing through the tube (A).

Variations from the foregoing description may be made to control the hydraulic forces and the easy passage of the liquid so that the apparatus will work to the best advantage under certain specific conditions. Also the lever system (11) may be constructed of any form or arrangement of common lever machines such as gear wheels, compound levers or belted wheels, according to the limits of space or headroom specified in a given design. The weight device (14) may be any arrangement of resistances to give a cumulative pull on the balancing side of the fulcrum by which means the cost of manufacture may be reduced in cheaper and less accurate apparatus. Also where it is desirable to condense the vertical height of the apparatus, the cumulative resistances or the complete counter-balancing device may operate in a water tight receptacle as (19), the bottom of which can then be placed immediately above the tube (A) without submerging any portion of the balancing device.

The counterbalancing weights 15, Fig. 3, are relatively loosely connected so that they are lifted or lowered successively, and, as here shown, are connected by links or hooks 15' of such length that each weight has a

small degree of free movement relative to those above and below. As the lever 11 swings up the slack is taken up between the links or hooks 15' and the weights successively lifted. When the weights are at rest 70 upon each other the coördinate hooks slightly separate, as shown in Fig. 3.

Having thus described my invention, what I claim and desire to secure by Letters Patent is—

75

1. In a hydraulic apparatus, a liquid conductor, a transverse dam or wall thereat, having an aperture, a tube with one end arranged against the dam and communicating with the aperture and projecting from 80 the supply side of the dam, and a shutter for controlling the flow of liquid through said aperture pivoted transverse the tube and having its swinging edge opposing the current in the tube and adapted to substantially neutralize the tendency of the impacting current to close the shutter and being operable with variations in velocity of flow adjacent to said shutter.

85

2. In a hydraulic apparatus, a liquid conductor, a transverse wall in the conductor provided with an aperture, a tubular member communicating with the aperture of the wall, and a pivoted shutter for controlling the flow of liquid through the aperture of 90 the wall, said shutter having its swinging edge angularly disposed relative to the shutter for action thereon by the liquid.

90

3. In a hydraulic apparatus, a liquid conductor, an apertured transverse dam or 100 wall, a tubular member communicating with the aperture of said dam, a pivoted shutter having its swinging edge opposing the current of the liquid flow and having its free edge arranged to form a variable area for 105 controlling the flow to, and through said aperture, and means automatically operable with variations in velocity of flow adjacent to said shutter.

105

4. In a hydraulic apparatus, a liquid conductor, a transverse dam or wall thereat having an aperture, a tube with one end arranged against the wall and communicating with the aperture and projecting from 110 the supply side of the dam, and a shutter pivoted transverse the tube and having its swinging edge opposing the current in the tube, said shutter controlling the flow of liquid through said aperture and being operable with variations in velocity of flow 115 adjacent to said shutter.

115

5. In a hydraulic apparatus, a liquid conductor, a transverse dam or wall thereat having an aperture, a tube with one end arranged against the dam and communicating with the aperture and projecting from the supply side of the dam, and a shutter for controlling the flow of liquid through said aperture pivoted transverse the tube and having its swinging edge opposing the cur- 120

125

130

- rent in the tube and adapted to substantially neutralize the tendency of the impacting current to close the shutter and being operable with variations in velocity of flow 5 adjacent to said shutter.
6. In a hydraulic apparatus, a liquid conductor, a transverse dam or wall thereat having an aperture, a tube with one end arranged against the dam and communicating 10 with the aperture, and projecting from the supply side of the dam, a shutter for controlling the flow of liquid through said aperture pivoted transverse the tube and having its swinging edge opposing the current in the tube and adapted to substantially neutralize the tendency of the impacting current to close the shutter, said shutter being operable with variations in velocity of adjacent flow, and means connected to the 15 shutter for counterbalancing the variations in the forces of static pressure with change of velocity of flow adjacent to the shutter, said means governing the motion of said shutter.
- 20 7. In a hydraulic apparatus, a liquid conductor, a transverse dam or wall thereat having an aperture, a tube with one end arranged against the dam and communicating with the aperture and projecting from the supply side of the dam, a shutter for controlling the flow of liquid through said aperture pivoted transverse the tube, and having its swinging edge opposing the current in the tube, and adapted to substantially neutralize the tendency of the impacting current to close the shutter, said shutter being operable with variations in velocity of flow 25 adjacent to the shutter, and means connected to the shutter for counterbalancing variations in forces of static pressure with change in velocity of flow adjacent to the shutter, said means governing the motion of the shutter, and including a cumulative variable resistance.
- 30 8. In a hydraulic apparatus, a liquid conductor, a dam transverse the conductor and having an aperture, a tube projecting toward the supply, and a shutter for controlling the flow of liquid through said aperture in the tube on the supply side of the 35 dam and operable by the variations in the resultant of two forces, the static pressure of the liquid supply in the conductor outside the tube, and the lesser static pressure of the volume of liquid flowing through the tube to the aperture.
- 35 9. An automatically operable, hydraulic apparatus for controlling or measuring, indicating and recording the flow of liquid consisting of a conductor, a shutter therein directly subjected to the hydraulic pressures therein and directly operable thereby for controlling the flow, a cumulative variable resistance mechanism governing the movements of the shutter, and measuring 40 indicating and recording mechanism actuated in accordance with said shutter.
- 40 10. In a hydraulic apparatus, a liquid conductor, a dam transverse the conductor and having a discharge aperture, a tube projecting toward the supply, a shutter for controlling the flow of liquid through said aperture in the tube on the supply side of the 45 dam and operable by the variations in the resultant of two forces, the static pressure of the liquid supply in the conductor outside the tube and the lesser static pressure of the volume of liquid flowing through the tube to the aperture, and a cumulative variable resistant mechanism connected to 50 the shutter for controlling the movement thereof.

In testimony whereof I have hereunto set my hand in the presence of the subscribing witnesses.

PAUL BAILEY.
